UNITED STATES PATENT OFFICE.

SADIE A. GALPIN, OF JEFFERSON, OHIO.

DESIGN FOR A SPOON.

51,369.

Specification for Design.

Patented Oct. 16, 1917.

Application filed May 28, 1917. Serial No. 171,587. Term of patent 3½ years.

To all whom it may concern:

Be it known that I, SADIE A. GALPIN, a citizen of the United States of America, residing at Jefferson, in the county of Ashtabula and State of Ohio, have invented a certain new, original, and ornamental Design for a Spoon, of which the following is a specification, reference being had therein to the accompanying drawing.

Copies of this patent may be obtained for five cents each, by addressing the "Commissioner of Patents, Washington, D. C."

Fig. 2 is a longitudinal section through a spoon, showing my new design.

I claim:—

The ornamental design for a spoon as shown.

In testimony whereof I hereunto affix my signature.

SADIE A. GALPIN.
